UNITED STATES PATENT OFFICE.

ROBERT E. GURLEY, OF CHICAGO, ILLINOIS, ASSIGNOR TO T. W. SNOW CONSTRUCTION COMPANY, OF CHICAGO, ILLINOIS, A CORPORATION OF ILLINOIS.

HOISTING MECHANISM.

1,404,287.

Specification of Letters Patent. Patented Jan. 24, 1922.

Application filed June 21, 1919. Serial No. 305,822.

To all whom it may concern:

Be it known that I, ROBERT E. GURLEY, a citizen of the United States, residing at Chicago, in the county of Cook and State of Illinois, have invented a new and useful Improvement in Hoisting Mechanism, of which the following is a specification.

My invention relates as to certain features thereof, generally to machines involving a member adapted to be moved in opposite directions, with means for effecting such movements of the member automatically, such as for example, automatically operating hoists, planers and other structures; and as to the other features thereof to hoists and the like machines.

My objects, generally stated, are to provide for the operation of a member adapted to be moved in opposite directions, in such a manner that a sufficient interval of time will lapse between the engagement of the driving means therewith for moving it in one direction and the engagement of such means for moving it in the opposite direction; and that such intervals will occur at the proper time relative to the operation of such member throughout the continued operation of the latter.

Further objects, and these more particularly in connection with the employment of my invention in hoist mechanism, are to provide novel, simple, positive and safely operating means for automatically operating the hoist in opposite directions, with the lapsing of the desired intervals of time between the automatic stopping of the hoist in its movement in one direction and the automatic starting of the hoist to move it in the opposite direction; to provide in a hoist employing means preventing the rotation of the hoist in a reverse direction under the action of the load, means whereby the braking means just referred to will be automatically positioned for operation in the rotation of the hoist in either direction should a condition occur wherein the weight of the load reversely operates the hoist, and will remain in position to operate as a brake for the hoist during the time that the driving means are disconnected therefrom in the reversing operation and until the load on the hoist and which would reverse the hoist if the machine should break or the power fail,

has been removed; to provide means for accomplishing the above stated results, which may be applied to automatic-stopping hoist machines as commonly provided; and other objects as will be manifest from the following description.

I have devised my improvements for use more particularly in connection with hoisting machines, such for example, as the kind shown in U. S. Patent No. 963,384, granted to R. A. Ogle, July 5, 1910, and have therefore chosen to illustrate them as embodied in a machine of this general construction, though without intending to limit the invention thereto.

Referring to the accompanying drawings—

Figure 1 is a view in side elevation of a hoisting machine embodying my improvements. Figure 2 is a plan view of the machine of Fig. 1, with a portion of a shaft broken away. Fig. 3 is a section taken at the irregular line 3—3 on Fig. 2 and viewed in the direction of the arrows, certain parts being broken away. Fig. 4 is a broken section taken at the line 4 on Fig. 2 and viewed in the direction of the arrow; and Fig. 5, a view in sectional elevation of one of the similar dash-pot mechanisms employed.

As a preface to the following description, it may be stated that the hoist as shown is adapted to be employed for the operation of a pair of buckets (not shown) moving in opposite directions or a single bucket in which case the cable at the end thereof not connected with a bucket, carries a counter-weight which is heavier than the empty bucket on the other end of the cable, the buckets where two are employed being so disposed with relation to loading pits and dumping points that one bucket is down in its co-operating pit and is being loaded, while the other bucket is elevated to the dumping position, and is dumping.

The frame 7 of the hoist comprises two side members 8 and 8' spaced apart, as represented and provided at their upper ends with bearings 9 and 10 in which two shafts 11 and 12 extending transversely of the machine, are journaled. The shaft 12 carries intermediate its ends, a drum 13, about which the cable (not shown) to the opposite ends of which the buckets referred to would

be attached, is wound. This drum is rotatable on the shaft 12, it being adapted to be clutched to the latter by means of a clutch (not shown), but operated through the medium of a lever 14 fulcrumed at 15 on the frame of the machine, this lever being shown in the drawings in a position for clutching the drum 13 to the shaft 12. The drum 13 has rigidly secured thereto a sprocket 16 for a purpose hereinafter described.

The drive-shaft represented at 17 is journaled in bearings 18 at the opposite sides of the frame 7, and carries towards its opposite ends pinions 19 and 20, which are freely rotatable thereon and are adapted to be alternately clutched to the shaft 17 by clutches 21 and 22, respectively, operating in a well-known manner through the medium of a horizontally swinging lever 23 fulcrumed between its ends, as indicated at 24, on a stationary sleeve 25 surrounding a shaft 26 journaled in bearings 27 (one only of which is shown) on the frame 7 at opposite sides thereof and held against longitudinal movement thereon by sleeves 28 and 29 on the shaft 26.

The shaft 11 carries at one end a gear 30 rigidly secured thereto and meshing with the pinion 20 and a pinion 31 fixed on the shaft 26, and at its opposite end a pinion 32 meshing with a gear 33 fixed on the shaft 12, the shaft 26 also carrying a pinion 34 secured thereto and meshing with the pinion 19. Thus when the clutch 22 is thrown in, the gears 19, 34 and 31 operate idly and the gear 30 is driven from the pinion 20 direct for driving the shaft 12 and its drum in one direction, whereas when the clutch 21 is thrown in, the gear 30 is driven through the medium of the gears 19, 34 and 31, thus reversing its direction of movement and that of the shaft 12 and the drum carried thereby.

The hoist, as shown, is provided with means for controlling the movement of the drum 13 in opposite directions and applying a brake to the drum in the event of the breaking of a part of the machine or the failure of power, which would allow the drum to run free, these means being automatic and of which the following is a description. Journaled in bearings 35 on the frame-sides is a shaft 36 carrying a crank 37, the crank-pin 38 of which is equipped with a roller 39 located within an aperture 40 provided in the upper end of a rock-arm 41 pivoted at its lower end at 42 to the frame of the machine, this arm surrounding at its opening 40 the shaft 36 and being adapted to be rocked on its fulcrum 42 by the rotation of the crank 37. The upper end of the arm 41 is pivotally connected at 43 with one end of a rod 44, the opposite end of this rod being pivotally connected at 45 at a yoke 65 thereon, with one end of the bell-crank 23,

whereby the rocking of the shaft 36 in opposite directions alternately moves the clutches 21 and 22 into operative position. Rotatably mounted on the shaft 36 is a yoke-shaped frame 46, opposite sides of which contain longitudinally-extending slots (not shown), but corresponding with the slots in the corresponding yoke member of the said patent, these slots serving as guides for the ends 47 of a pawl device 48 having screw-threaded connection with the threaded portion 39 of the shaft 36 within the confines of the frame 46. The frame 46 is rigid with a sprocket-wheel 50, connected by a chain 51 with the sprocket-wheel 16, whereby in the rotation of the drum 13 the yoke 46 and the pawl device 48 are rotated and the latter is carried along the shaft 36 by reason of its threaded connection therewith in one direction or the other in Fig. 2, depending on the direction in which the drum 13 is rotated. The pawl device 48 is formed on its opposite faces with oppositely disposed shoulders 51 and 52, which are adapted to alternately engage with shoulders 53 and 54, respectively, formed on dogs 55 and 56, rigidly secured to the shaft 36, but adjustable lengthwise thereon by clamping means indicated at 157 and 57^a, respectively, whereby engagement of the shoulders 51 and 52 with their respective co-operating shoulders 53 and 54 operate to rock the shaft 36 for moving the drive-shaft clutch-mechanism to normal inoperative and neutral position for stopping the machine, as is hereinafter more fully explained. Looped about the periphery of a flange 57 on the drum 13, is a brake-strap 58, the inner surface of which is provided with friction blocks 59 of wood, or any other suitable material, spaced apart, the lower ends of the strap 58 being pivotally connected at 60 with an upwardly extending arm 61 rigidly secured to a shaft 62 journaled in the frame 7 at opposite sides of the machine, this shaft being equipped with an upwardly extending arm 63 carrying a weight 64 at its upper end and pivotally connected as indicated at 65 with a link 66 which extends into the space between a pair of segmental plates 67 spaced apart and rigidly secured to the shaft 36, this end of the link 66 carrying a cross-pin 68 which extends into opposed arc-shaped slots 69 arranged in the plates 67 concentrically of the axis of the shaft 36. The brake-strap 58 is so adjusted about the drum flange 57 that when the parts of the mechanism are in neutral position hereinafter referred to, the band brake formed of the strap 58 and blocks 59 extends loosely about the drum flange 57, but when the arm 61 is shifted to either side of the vertical position, the brake-band will be in position for gripping the drum in case of accident effecting reversal of the latter as hereinafter more fully explained. The outer end of the shaft 130

36 is equipped with an arm 165 carrying a weight 166, this weighted arm co-operating with a rock-frame 167 of general V-shape form fulcrumed at its lower end on a pin 168 to the frame 7. The frame 167 is formed of two similar bars 169 of the shape referred to, these bars being connected together through the medium of cross-pins 70, 71, 72^a and 73^a, the pins 70 and 71 being located 5 at the extremities of the member 167 and the pins 72^a and 73^a between the extremities thereof and the pivot 168. The lever 165 is so positioned that it extends in a plane between the planes occupied by the bars 169 10 and thus in one position engages the pin 71 as shown in the drawings, and in the other position, hereinafter referred to, engages the pin 70, the frame 167 being rocked in opposite directions on its pivot 168 by the engagement therewith of the lever 165. Mounted 15 below the frame 167 are devices for cushioning the movement of the frame 167 in opposite directions and controlling the speed at which this frame rocks under the action of 20 the weighted lever 165, for the purpose hereinafter explained. These devices comprise cylinders 72 and 73 fulcrumed at their lower ends, as indicated at 74 and 75, respectively, 25 on the frame of the machine, these cylinders containing pistons (the one for the cylinder 30 73 being represented at 75), which are connected, respectively, with piston-rods 76 and 77, pivotally connected, respectively, with the pins 72^a and 73^a. Each cylinder is 35 formed on its inner surface with a by-pass 78 opening at its upper and lower ends into the interior of the cylinder and at its lower end contains a valved vent 79.

The operation of the apparatus is as follows: The machine is shown in the position it assumes during the driving of the drum 13 in one direction, namely, in clockwise direction in Fig. 1, the drive being 40 from the shaft 17 through the clutch 22, gear 20, gear 30, shaft 11, gear 32, gear 33 to drum 13, thus rotating the yoke 46 in clockwise direction in Fig. 1, which causes 45 the pawl device 48 to move along the yoke 46 toward the dog 55. In the continued 50 movement of the parts as stated, the tooth 51 engages the tooth 53 on the dog 55, thus rotating the shaft 36 in clockwise direction in Fig. 1; with the result of throwing the lever 165 to the right in Fig. 1, to a position 55 in which it extends to the right beyond perpendicular position, and the crank-arm 37 is rotated in the aperture 40 of the arm 41. In the rotation of the crank-arm 37 against the arm as stated, the clutch-lever 60 23 is rocked in clockwise direction in Fig. 2, with the result of shifting the clutch mechanisms on the shaft 17 to a position 65 in which neither the gear 19 nor the gear 20 is clutched to this shaft, or in other words, to a position where the parts are in neutral

condition. The lever 165 by moving to the right of the perpendicular, before the drive of the drum 13 from the shaft 17 is discontinued, operates by its weight to continue the movement of the shaft 36 in clockwise direction in Fig. 3 to a position in which the crank 37 is diametrically opposed to the position thereof shown in Fig. 3, in moving to which position the lever 23 is rocked in clockwise direction in Fig. 2 to 70 a position in which the gear 19 is clutched to the shaft 17 through the medium of the clutch 21, whereupon the drive of the drum 13 is reversed, it being then driven from the shaft 17, clutch 21, gears 19 and 34, shaft 80 26, gears 31 and 30, shaft 11 and gears 32 and 33.

In the movement of the lever 165 to rotate the shaft 36 for throwing in the clutch 21 as stated, the lever 165 bears against the 85 pin 70, thereby rocking the frame 167 in clockwise direction in Fig. 1, this movement of the member 167 being retarded by the dash-pot mechanism involving the cylinder 72, which operates to cause the initial rocking movement of the member 167 to be relatively slow, its movement being regulated by the extent to which the valve 79 of the cylinder 72 is opened, but after the piston passes the upper end of the by-pass 78, 90 it lowers relatively quickly until it reaches practically the end of its downward movement, the air in the bottom of the cylinder then operating as a cushion. The parts of the structure are so constructed and arranged 95 that during the movement of the piston to a point where it uncovers the upper end of the by-pass 78 to the atmosphere, the clutches 21 and 22 are in neutral position, the clutch 21 clutching the gear 19 to the shaft 17 in 105 the movement of the piston 75 below the point at which the by-pass 78 communicates at its upper end with the atmosphere, with the result of causing the clutch 21 to be relatively quickly shifted into position following the interval during which it is in 110 neutral position.

The brake mechanism referred to when in the position shown in the drawings, operates to permit the shaft 12 to freely rotate in 115 clockwise direction in Fig. 1, but should this shaft start to rotate in the opposite direction, with the parts in the position shown in the drawings, as for example, under the action of a loaded bucket, should an accident 120 occur or should the power be cut off, the brake mechanism referred to will immediately grip the drum flange 57 and lock the drum against rotation.

From the foregoing description it will be 125 understood that in the rotation of the shaft 36 in clockwise direction in Fig. 1, as above explained, the plates 67 will, during a portion of the movement of this shaft, rotate at their slotted portions 69 on the pin 68 without 130

moving the lever 63, but as soon as the ends of these slots shown uppermost in Fig. 4, move to a position in which they strike the pin 68, the lever 63, upon continued rotation of the shaft 36, is shifted to the left in Fig. 4 by means of the link 66, thereby swinging the lever 61 to the left in this figure and so positioning the brake device formed of the band 58 and blocks 59 that it 10 will permit the shaft 12 to rotate freely in anti-clockwise direction in Fig. 1, but serve as a brake for the shaft should conditions cause it to reversely rotate. The parts of the mechanism just described, in practice are 15 so constructed and arranged that the arm 63 will remain in the position shown in Fig. 1 until the conditions are such that the force tending to rotate the drum reversely has been removed, as for example, when two 20 buckets are employed, until the force exerted by the loaded bucket, on the drum tending to rotate it reversely has become so reduced, as in the discharging of its contents, that the drum is not subjected to a force tending 25 to reversely rotate it, in the particular construction shown, the arm 63 remaining in the position shown in Fig. 1 until the mechanism rocking the lever 23 has moved automatically, as hereinbefore explained, to a position 30 in which the clutch 21 starts to grip the gear 19 to the shaft 17 which occurs after the load tending to reverse the drum has been removed. Thus while the drive for the drum is in neutral position, the brake device 35 remains set in such position that should the drum then begin to reversely rotate, as for example, by the breaking of a part of the machine or by discontinuance of the supplying of power to the machine while a 40 load is exerting a force on the drum tending to rotate it reversely, the drum in such reverse rotation will be immediately arrested.

In the rotation of the drum 13 in counter-clockwise direction in Fig. 1, following the 45 shifting of the clutch 21 into operative position as hereinbefore explained, the yoke 46 is also rotated in anti-clockwise direction in Fig. 1, thus causing the pawl 48 to move along the frame 46 on the threaded portion 50 49 of the shaft 36 toward the dog 56, the pawl 48 engaging at its shoulder 52 with the shoulder 54 on the dog 56, in the movement of the pawl 48 as stated, thus rotating the shaft 36 in anti-clockwise direction in Fig. 55 1, which throws the lever 165 to the left in the drawings beyond the perpendicular, in which position it opposes the pin 71 and rocks the rock-member 167 in anti-clockwise direction in Fig. 1, the dash-pot mechanism 60 involving the cylinder 73 operating to retard the lowering of the lever 165 and consequently the rotation of the shaft 36, in the same manner in which the other dash-pot mechanism retarded the movement of the 65 lever 165 in clockwise direction in Fig. 1

as hereinbefore explained, the rotation of the shaft 36 in anti-clockwise direction as stated operating to first shift the clutches on the shaft 17 into neutral condition and following this operation, clutching the gear 70 20 to this shaft through the medium of the clutch 22, the arm 63 in the final movement of the shaft 36 in anti-clockwise direction shifting to the position shown in Fig. 4, just as the clutch 22 goes in, for so positioning 75 the brake device formed of the band 58 and blocks 59, that the drum may rotate freely in clockwise direction in Fig. 1, but be arrested in case it starts to reversely rotate. 80

It will be understood from the foregoing that by the provision of the mechanism as stated there is a lapsing of a predetermined length of time between the disengagement of one clutch controlling the driving of the 85 drum in one direction and the engagement of the clutch controlling the driving of the drum in the opposite direction, this interval being afforded for the purpose of effecting the loading and the dumping of the buckets 90 in alternation with the hoisting operations, it being understood that the length of this interval may be readily varied, as desired, as by adjusting the valves 79.

It will be noted that the automatically- 95 operating drum-reversing-and-brake-controlling mechanism is operated at all times synchronously with the drum, in the particular construction illustrated by the direct drive connection through the sprocket-chain 100 51 between the drum and this mechanism, and thus even should the clutches slip, it will not affect the operation of the mechanism referred to in properly timed relation to the drum. 105

If desired the mechanism may be rendered non-automatic as to the reversing operation, by removing the weight 166, and the lever 165 is then operable by hand to reverse the rotation of the drum. 110

While I have illustrated a particular construction embodying my invention and shown it as applied to a certain type of device, I do not wish to be understood as intending to limit it thereto, as the invention 115 may be provided in other forms and employed in connection with other kinds and types of machines.

What I claim as new and desire to secure by Letters Patent is: 120

1. The combination of a driving member, mechanism driven thereby and including a second member adapted to be moved in opposite directions, and means adapted to drive said second member from said driving member in opposite directions alternately and including clutch mechanism, and means operated by said first-referred to mechanism and operating automatically upon said clutch mechanism, to cause the said first-named 125 130

means to operate said second member automatically in opposite directions involving a rock-member actuated in opposite directions by said mechanism said rock-member having

5 a portion disposed eccentrically of the axis of said rock-member, which, in the actuations of said rock-member is moved beyond perpendicular position and operates to finish the throw of said rock-member for effecting
10 the shifting of the clutch mechanism to re-

verse the movement of said second member.

2. The combination of a driving member, mechanism driven thereby and including a second member adapted to be moved in oppo-

15 site directions, and means adapted to drive said second member from said driving member in opposite directions alternately, and means operated by said mechanism and operating automatically upon said first-named

20 means, to cause the latter to operate said second member automatically in opposite directions involving a rock-member actuated in opposite directions by said mechanism, said rock-member having a portion disposed

25 said rock-member having a portion disposed eccentrically of the axis of said rock-member, which, in the actuations of said rock-member is moved beyond perpendicular position and operates to finish the throw of said rock-member for effecting the reversal of the
30 movement of said second member, and means

movement of said second member, and means for regarding the movement of said rock-member under the action of said eccentrically disposed portion.

3. The combination of a driving member, mechanism driven thereby and including a second member adapted to be moved in opposite directions and means adapted to drive said second member from said driving member in opposite directions alternately and

40 be in opposite directions alternately, and means operated by said mechanism and operating automatically upon said first-named means, to cause the latter to operate said second member automatically in opposite directions involving a rock-member actuated

45 in opposite directions by said mechanism, said rock-member having a portion disposed eccentrically of the axis of said rock-member, which, in the actuations of said rock-member is moved beyond perpendicular position and operates to finish the throw of

50 action and operates to finish the throw of said rock-member for effecting the reversal of the movement of said second member, and dash-pot mechanism for retarding the movement of said rock-member under the action
55 of said eccentrically disposed portion.

4. The combination of a driving member, mechanism driven thereby and including a second member adapted to be moved in opposite directions and means adapted to drive the second member in opposite directions.

60 opposite directions and means adapted to drive said second member from said driving member in opposite directions alternately, and means operated by said mechanism and operating automatically upon said first named

erating automatically upon said first-named means, to cause the latter to operate said 65 second member automatically in opposite

directions involving a rock-member actuated in opposite directions by said mechanism, said rock-member having a portion disposed eccentrically of the axis of said rock-member, which in the actuations of said rock-member is moved beyond perpendicular position and operates to finish the throw of said rock-member for effecting the reversal of the movement of said second member, and a rock-frame operated in opposite directions by engagement therewith of said rock-member in its movement in opposite directions, and rocking under the action of said rock-member. 70 75

5. The combination of a driving member, 80 mechanism driven thereby and including a second member adapted to be moved in opposite directions, and means adapted to drive said second member from said driving mem-

said second member from said driving member in opposite directions alternately, and means operated by said mechanism and operating automatically upon said first-named means, to cause the latter to operate said second member automatically in opposite 85

second member automatically in opposite directions involving a rock-member actuated in opposite directions by said mechanism, said rock-member having a portion disposed eccentrically of the axis of said rock-member, which, in the actuations of said rock-member is moved beyond perpendicular po- 95

member is moved beyond perpendicular position and operates to finish the throw of said rock-member for effecting the reversal of the movement of said second member, a

rock-frame operated in opposite directions by engagement therewith of said rock-member in its movement in opposite directions, and rocking under the action of said rock-member, and means for retarding the movement of said rock-frame in opposite directions.

6. The combination of a driving member, 105 mechanism driven thereby and including a second member adapted to be moved in opposite directions, and means adapted to drive

posite directions, and means adapted to drive said second member from said driving member in opposite directions alternately, and means operated by said mechanism and operating automatically upon said first-named

means, to cause the latter to operate said second member automatically in opposite directions involving a rock-member, actuated 115 in opposite directions by said mechanism, said rock-member having a portion disposed

eccentrically of the axis of said rock-member, which, in the actuations of said rock-member is moved beyond perpendicular position and operates to finish the throw of said rock-member for effecting the reversal 120

of the movement of said second member, a rock-frame operated in opposite directions by engagement therewith of said rock-member 125 in its movement in opposite directions, and rocking under the action of said rock-

and locking after the action of said rock-member, and dash-pot mechanism for retarding the movement of said rock-frame in opposite directions.

7. The combination of a driving member, mechanism driven thereby and including a second member adapted to be moved in opposite directions and means adapted to drive said second member from said driving member in opposite directions alternately, and means operated by said mechanism and operating automatically upon said first-named means, to cause the latter to operate said second member automatically in opposite directions involving a rock-member actuated in opposite directions by said mechanism, said rock-member having a portion disposed eccentrically of the axis of said rock-member, which, in the actuations of said rock-member is moved beyond perpendicular position and operates to finish the throw of said rock-member for effecting the reversal of the movement of said second member, a rock-frame operated in opposite directions by engagement therewith of said rock-member in its movement in opposite directions, and rocking under the action of said rock-member, and adjustable means for retarding the movement of said rock-frame in opposite directions.
8. The combination of a driving member, mechanism driven thereby and including a second member adapted to be moved in opposite directions, and means adapted to drive said second member from said driving member in opposite directions alternately, and means operated by said mechanism and operating automatically upon said first-named means, to cause the latter to operate said second member automatically in opposite directions involving a rock-member actuated in opposite directions by said mechanism, said rock-member having a portion disposed eccentrically of the axis of said rock-member, which, in the actuations of said rock-member is moved beyond perpendicular position and operates to finish the throw of said rock-member for effecting the reversal of the movement of said second member, a rock-frame operated in opposite directions by engagement therewith of said rock-member in its movement in opposite directions, and rocking under the action of said rock-member, and adjustable dash-pot mechanism for retarding the movement of said rock-frame in opposite directions.
9. The combination of a driving member, mechanism driven thereby and including a second member adapted to be moved in opposite directions, and means adapted to drive said second member from said driving member in opposite directions alternately, and means operated by said mechanism and operating automatically upon said first-named means, to cause the latter to operate said second member automatically in opposite directions, including a device operated by said mechanism for automatically operating upon said first-named means to cause the latter to

be in neutral position, in which said second member is out of driving engagement with said driving member, and a device operating to thereafter cause said first-named means to be in a position for driving said second member in a reverse direction. 70

10. The combination of a driving member, mechanism driven thereby and including a second member adapted to be moved in opposite directions and means adapted to drive said second member from said driving member in opposite directions alternately, and means operated by said mechanism and operating automatically upon said first-named means, to cause the latter to operate said second member automatically in opposite directions, including a device operated by said mechanism for automatically operating upon said first-named means to cause the latter to be in neutral position in which said second member is out of driving engagement with said driving member, and a device operating to thereafter cause said first-named means to be in a position for driving said second member in a reverse direction, 80 and means for regulating the interval during which said second member is out of driving engagement with said driving member. 85

11. The combination of a driving member, mechanism driven thereby and including a second member adapted to be moved in opposite directions and means adapted to drive said second member from said driving member in opposite directions alternately and including clutch mechanism, and means operated by said first-referred-to mechanism and operating automatically upon said clutch mechanism, to cause the said first-named means to operate said second member automatically in opposite directions involving a rock-member actuated in opposite directions by said mechanism, said rock-member having a portion disposed eccentrically of the axis of said rock-member, which, in the actuations of said rock-member is moved beyond perpendicular position and operates to finish the throw of said rock-member for effecting the shifting of the clutch mechanism to reverse the movement of said second member, and means operating automatically to move said rock-member to a position in which said eccentrically disposed portion extends beyond perpendicular position. 100 110

12. The combination of a driving member, mechanism driven thereby and including a second, rotatable, member adapted to be rotated in opposite directions and means adapted to drive said second member from said driving member in opposite directions alternately in opposition to a force tending to reverse the rotation of said second member, brake mechanism cooperating with said rotatable member and shiftable to position said brake mechanism for automatically 120 125 130

- stopping said rotatable member in its rotation in either direction when reversely rotated by such a force, and means operating automatically upon said first-named means 5 to cause the latter to operate said second member automatically in opposite directions and automatically shift said brake mechanism to position the latter for automatic operation in the reverse rotation of said 10 rotatable member by such a force.
13. The combination of a driving member, mechanism driven thereby and including a second, rotatable, member adapted to be rotated in opposite directions and means 15 adapted to drive said second member from said driving member in opposite directions alternately in opposition to a force tending to reverse the rotation of said second member, brake mechanism cooperating with said 20 rotatable member and shiftable to position said brake mechanism for automatically stopping said rotatable member in its rotation in either direction when reversely rotated by such a force, and means operated 25 by said mechanism and operating automatically upon said first-named means to cause the latter to operate said second member automatically in opposite directions and automatically shift said brake mechanism to 30 position the latter for automatic operation in the reverse rotation of said rotatable member by such a force.
14. The combination of a driving member, mechanism driven thereby and including a 35 second, rotatable, member adapted to be rotated in opposite directions and means adapted to drive said second member from said driving member in opposite directions alternately in opposition to a force tending 40 to reverse the rotation of said second member, brake mechanism cooperating with said rotatable member and shiftable to position said brake mechanism for automatically stopping said rotatable member in its rotation 45 in either direction when reversely rotated by such a force, and means actuated by said second member and operating automatically upon said first-named means to cause the latter to operate said second member 50 automatically in opposite directions and automatically shift said brake mechanism to position the latter for automatic operation in the reverse rotation of said rotatable member by such a force.
15. The combination of a driving member, mechanism driven thereby and including a second, rotatable, member adapted to be rotated in opposite directions and means adapted to drive said second member from 55 said driving member in opposite directions alternately in opposition to a force tending to reverse the rotation of said second member, brake mechanism cooperating with said 60 rotatable member and shiftable to position said brake mechanism for automatically stopping said 65 rotatable member in its rotation in either direction when reversely rotated by such a force.
16. The combination of a driving member, mechanism driven thereby and including a second, rotatable, member adapted to be rotated in opposite directions and means adapted to drive said second member from 70 said driving member in opposite directions alternately in opposition to a force tending to reverse the rotation of said second member to position said braking element for automatic operation in the reverse rotation of said rotatable member by such a force. 75
17. The combination of a driving member, mechanism driven thereby and including a second, rotatable, member adapted to be rotated in opposite directions and means adapted to drive said second member from 80 said driving member in opposite directions alternately in opposition to a force tending to reverse the rotation of said second member, a shiftable band-brake cooperating with said second member and operating automatically when shifted in opposite directions, to stop said second member in its rotation in either direction when reversely rotated by such a force, and means operating 85 automatically upon said first-named means to cause the latter to operate said second member automatically in opposite directions and automatically shift said band-brake to position the latter for automatic operation in the reverse rotation of said second member by such a force. 90
18. The combination of a driving member, mechanism driven thereby and including a second, rotatable, member adapted to be rotated in opposite directions and means adapted to drive said second member from 95 said driving member in opposite directions alternately in opposition to a force tending to reverse the rotation of said second member, a band-brake, a movable member to which said band-brake is connected operating when moved in opposite directions to position the brake for stopping said second member in either direction of movement, when reversely rotated, under the action of such a force, and means operating automatically upon said first-named means to cause the latter to operate said second member automatically in opposite directions and automatically shift said movable member, for the purpose set forth. 100
19. The combination of a driving member, mechanism driven thereby and including a second, rotatable, member adapted to be rotated in opposite directions and means adapted to drive said second member from 105 said driving member in opposite directions alternately in opposition to a force tending to reverse the rotation of said second member, a band-brake, a rock-shaft, an arm on said rock-shaft and connected with said 110
20. The combination of a driving member, mechanism driven thereby and including a second, rotatable, member adapted to be rotated in opposite directions and means adapted to drive said second member from 115 said driving member in opposite directions alternately in opposition to a force tending to reverse the rotation of said second member, a band-brake, a rock-shaft, an arm on said rock-shaft and connected with said 120
21. The combination of a driving member, mechanism driven thereby and including a second, rotatable, member adapted to be rotated in opposite directions and means adapted to drive said second member from 125 said driving member in opposite directions alternately in opposition to a force tending to reverse the rotation of said second member, a band-brake, a rock-shaft, an arm on said rock-shaft and connected with said 130

band-brake and operating when actuated in opposite directions to shift the band-brake and move its connection with said arm out of alignment with the axes of said second 5 member and said rock-shaft from one side to the other, and means operating automatically upon said first-named means to cause the latter to operate said second member automatically in opposite directions and automatically 10 shift said rock-shaft, for the purpose set forth.

19. The combination of a driving member, mechanism driven thereby and including a second, rotatable, member adapted to be rotated in opposite directions and means adapted to drive said second member from said driving member in opposite directions alternately in opposition to a force tending to reverse the rotation of said second member, a band-brake, a rock-shaft, an arm on said rock-shaft and connected with said band-brake and operating when actuated in opposite directions to shift the band-brake and move its connection with said arm out 20 of alignment with the axes of said second member and said rock-shaft from one side to the other, said rock-shaft carrying an eccentrically disposed member adapted to move with said rock-shaft from one side to 25 the other of perpendicular position and exert a pulling action on said band-brake, and means operating automatically upon said first-named means to cause the latter to operate said second member automatically in 30 opposite directions and automatically rock said rock-shaft in opposite directions, for the purpose set forth.

20. In mechanism of the character set forth, the combination of a cable-driving 40 drum rotatable in opposite directions in opposition to a force tending to reverse the rotation of said drum, a drive-shaft, gear mechanisms interposed between said drive-shaft and drum, a pair of clutches adapted 45 to alternately engage with said shaft to alternately actuate said gear mechanisms for driving the drum in opposite directions, a rock-member provided with a crank portion, a band-brake cooperating with said 50 drum and connected with said crank portion, an arm on said rock-shaft and adapted to move in the movement of said rock-shaft in opposite directions, from one side to the other of perpendicular position, a second 55 rock-shaft, means operated by said drum in the movement of the latter in one direction for actuating said second rock-shaft in one direction after said drum has rotated in one direction a predetermined number of 60 times and for actuating said second rock-shaft in the opposite direction when said drum has rotated in the opposite direction a predetermined number of times and means actuated by said second shaft for shifting 65 said clutches, means actuated by said sec-

ond rock-shaft for rocking said first referred to rock-shaft in opposite directions, and means operating automatically to actuate said second rock-shaft for automatically reversing the rotation of said drum. 70

21. The combination of a driving member, mechanism driven thereby and including a second, rotatable, member adapted to be rotated in opposite directions and means adapted to drive said second member from said driving member in opposition to a force tending to reverse the rotation of said second member, brake mechanism cooperating with said mechanism and shiftable to position said brake mechanism for automatically stopping said rotatable member in its rotation when reversely rotated by such a force, means for disconnecting said first-named mechanism from said driving member, and automatically operating means for shifting said brake members constructed and arranged to permit said brake mechanism to remain in operative position for performing the braking function until after the force tending to reversely rotate said second member has been removed. 80

22. The combination of a driving member, mechanism driven thereby and including a second, rotatable, member adapted to be rotated in opposite directions and means adapted to drive said second member from said driving member in opposite directions alternately in opposition to a force tending to reverse the rotation of said second member, brake mechanism cooperating with said first referred to mechanism and shiftable to position said brake mechanism for automatically stopping said rotatable member in its rotation in either direction when reversely rotated by such a force, means operating automatically to disconnect said first-named mechanism from said driving member, and automatically operating means for shifting said brake mechanism constructed and arranged to permit said brake mechanism to remain in operative position for performing the braking function until after the force tending to reversely rotate said second member has been removed. 90

23. The combination of a driving member, mechanism driven thereby and including a second, rotatable, member adapted to be rotated in opposite directions and means adapted to drive said second member from said driving member in opposition to a force tending to reverse the rotation of said second member, brake mechanism cooperating with said first-named mechanism and shiftable to position said brake mechanism for automatically stopping said rotatable member in its rotation when reversely rotated by such a force, means for disconnecting said first-named mechanism from said driving member, and automatically operating means operated by said second member for shift- 100

ing said brake mechanism constructed and arranged to permit said brake mechanism to remain in operative position for performing the braking function until after the force 5 tending to reversely rotate said second member has been removed.

24. The combination of a driving member, mechanism driven thereby and including a second, rotatable, member adapted to 10 be rotated in opposite directions and means adapted to drive said second member from said driving member in opposite directions alternately in opposition to a force tending to reverse the rotation of said second member, brake mechanism cooperating with said first referred to mechanism and shiftable to position said brake mechanism for automatically stopping said rotatable member in its rotation in either direction when 15 reversely rotated by such a force, means operating automatically to disconnect said first-named mechanism from said driving member, and automatically operating means operated by said second member for shifting 20 said brake mechanism construction and arranged to permit said brake mechanism to remain in operative position for performing the braking function until after the force 25 tending to reversely rotate said second member has been removed.

25. The combination of a driving member, mechanism driven thereby and including a second, rotatable, member adapted to be rotated in opposite directions and means adapted to drive said second member from said driving member in opposition to a force tending to reverse the rotation of said second member, band-brake mechanism cooperating with said second member and involving 30 a band through the medium of which the braking is effected, and a rock-member operating when shifted to position said band for automatically stopping said rotatable member in its rotation when reversely rotated by such a force, means for disconnecting 35 said first-named mechanism from said driving member, and automatically operating means for shifting said rock-member constructed and arranged to permit said 40 brake mechanism to remain in operative position for performing the braking function until after the force tending to reversely rotate said second member has been removed.

26. The combination of a driving member, 45 mechanism driven thereby and including a second, rotatable, member adapted to be rotated in opposite direction and means adapted to drive said second member from said driving member in opposition to a force 50 tending to reverse the rotation of said second member, brake mechanism cooperating with said mechanism and shiftable to position said brake mechanism for automatically stopping said rotatable member in its rotation when reversely rotated by such a force,

and automatically operating means for shifting said brake mechanism constructed and arranged to permit said brake mechanism to remain in operative position for performing the braking function until after the force 70 tending to reversely rotate said second member has been removed.

27. The combination of a driving member, mechanism driven thereby and including a second member adapted to be moved in opposite directions and means including clutch mechanism adapted to drive said second member from said driving member in opposite directions alternately, and means operated by said first-named mechanism and operating automatically upon said clutch mechanism, to cause said first-named means to operate said second member automatically in opposite directions, including a device operated by said first-named mechanism for automatically operating upon said clutch mechanism to cause the latter to be in neutral position, in which said second member is out of driving engagement with said driving member, and a device operating to thereafter 80 cause said clutch mechanism to be in a position for driving said second member in a reverse direction.

28. The combination of a driving member, mechanism driven thereby and including a second member adapted to be moved in opposite directions and means including clutch mechanism adapted to drive said second member from said driving member in opposite directions alternately, and means operated by said first-named mechanism and operating automatically upon said clutch mechanism, to cause said first-named means to operate said second member automatically in opposite directions, including a device operated by said first-named mechanism for automatically operating upon said clutch mechanism to cause the latter to be in neutral position, in which said second member is out of driving engagement with said driving member, and a device operating to thereafter cause said clutch mechanism to be in a position for driving said second member in a reverse direction, and means for regulating the interval during which said second member is out of driving engagement with said driving member.

29. The combination of a driving member, mechanism driven thereby and including a second member adapted to be moved in opposite directions and means adapted to drive said second member from said driving member in opposite directions alternately, and means operating automatically upon said first-named means, to cause the latter to operate said second member automatically in opposite directions, including an automatically-operated device automatically operating upon said first-named means to cause the latter to be in neutral position, in which said 125

second member is out of engagement with said driving member, and a device operating to thereafter cause said first-named means to be in a position for driving said second member in a reverse direction.

30. The combination of a driving member, mechanism driven thereby and including a second member adapted to be moved in opposite directions and means adapted to drive said second member from said driving member in opposite directions alternately, and means operated by said mechanism and operating automatically upon said first-named means, to cause the latter to operate said second member automatically in opposite directions, including a device operated by said mechanism for automatically operating upon said first-named means to cause the latter to be in neutral position, in which said second member is out of driving engagement with said driving member, and a device operating after a predetermined time interval, to cause said first-named means to be in a position for driving said second member in a reverse direction.

31. The combination of a driving member, mechanism driven thereby and including a second member adapted to be moved in opposite directions and means adapted to drive said second member from said driving member in opposite directions alternately, and means operating automatically upon said first-named means to cause the latter to operate said second member automatically in opposite directions including a member which in its movements controls said first-named means and means for retarding the movement of said member thereby to produce a predetermined time interval between the arresting of the rotation of said second member and the beginning of the rotation thereof in the opposite direction.

32. The combination of a driving member, mechanism driven thereby and including a second member adapted to be moved in opposite directions and means, including clutch mechanism, adapted to drive said second member from said driving member in opposite directions alternately, and means operating automatically upon said clutch mechanism, to cause said first-named means to operate said second member automatically in opposite directions including an automatically-operating device automatically operating upon said clutch mechanism to cause the latter to be in neutral position, in which said second member is out of driving engagement with said driving member, a third member controlling the positioning of said clutch mechanism to drive said second member in the reverse direction, and means for retarding the movement of said third member, to cause a predetermined time interval to lapse between the arresting of the

movement of said second member and the commencement of its movement in the reverse direction.

33. The combination of a driving member, mechanism driven thereby and including a second, rotatable member adapted to be rotated in opposite directions and means adapted to drive said second member from said driving member in opposition to a force tending to reverse the rotation of said second member, brake mechanism co-operating with said mechanism and shiftable to position said brake mechanism for automatically stopping said rotatable member in its rotation when reversely rotated by such a force, automatically operating means for shifting said brake mechanism constructed and arranged to permit said brake mechanism to remain in operative position for performing the braking function until after the force tending to reversely rotate said second member has been removed, and means for causing a predetermined time interval to elapse between the arresting of the rotation of said second member and the commencement of its rotation in the opposite direction.

34. The combination of a driving member, mechanism driven thereby and including a second, rotatable member adapted to be rotated in opposite directions and means adapted to drive said second member from said driving member in opposition to a force tending to reverse the rotation of said second member, brake mechanism co-operating with said mechanism and shiftable to position said brake mechanism for automatically stopping said rotatable member in its rotation when reversely rotated by such a force, automatically operating means for shifting said brake mechanism constructed and arranged to permit said brake mechanism to remain in operative position for performing the braking function until after the force tending to reversely rotate said second member has been removed, and means for causing a predetermined time interval to elapse between the arresting of the rotation of said second member and the commencement of its rotation in the opposite direction, said last-named means being adjustable to vary the length of the said time interval.

35. The combination of a driving member, mechanism driven thereby and involving a second, rotatable, member adapted to be rotated in opposite directions and means adapted to drive said second member from said driving member in opposition to a force tending to reverse the rotation of said second member and including clutch mechanism and means operating automatically to shift said clutch mechanism into neutral condition and thereafter into a position wherein said second member is rotated re-

versely to the direction in which it was previously rotated, brake mechanism co-operating with said mechanism and shiftable to position said brake mechanism for automatically stopping said rotatable member in its rotation when reversely rotated by such a force, and automatically operating means

for shifting said brake mechanism constructed and arranged to permit said brake mechanism to remain in operative position 10 for performing the braking function until after the force tending to reversely rotate said second member has been removed.

ROBERT E. GURLEY.
